UNITED STATES PATENT OFFICE.

DAVID CHALMER SHARP AND WALTER R. DIEHL, OF PITTSBURGH, PENNSYLVANIA.

DRIVING LAMP FOR VEHICLES.

1,419,949.

Specification of Letters Patent. Patented June 20, 1922.

Application filed April 14, 1921. Serial No. 461,334.

To all whom it may concern:

Be it known that we, DAVID CHALMER SHARP and WALTER R. DIEHL, citizens of the United States, residing at Pittsburgh, 5 in the county of Allegheny and State of Pennsylvania, have invented certain new and useful Improvements in Driving Lamps for Vehicles, of which the following is a specification.

10 This invention relates to a driving lamp for use in conjunction with automobiles and other vehicles.

One object of the invention is to provide a lamp which is automatically rotated in a 15 horizontal plane by steering of the vehicle to which it is applied.

Another object of the invention is to provide means whereby the lamp may be rotated in a vertical plane independently of 20 the vertical rotation, but when so desired synchronously therewith.

In the accompanying drawings Fig. 1 is a side elevation of a lamp embodying the features of the present invention mounted 25 on the chassis of an automobile; Fig. 2 is a front elevation of two such lamps, so mounted and interconnected for simultaneous movement; Fig. 3 is a side elevation of the lamp and lamp bracket; Fig. 4 is a rear 30 elevation of the same; Fig. 5 is a vertical sectional view on the line 5—5 Fig. 3 illustrating a lamp assembly arranged for positive actuation; Fig. 6 is a vertical sectional view on the line 6—6 Fig. 4; Fig. 7 is a 35 front elevation of a manually operable lever for causing rotation of the lamp in a vertical plane; Fig. 8 is a side elevation thereof; Figs. 9, 10, and 11 are respectively a front elevation, side elevation, and a cross 40 section of a double crank comprising a portion of the operating means for causing horizontal rotation of the lamp; and Fig. 45 12 is an enlarged detail view of a portion of the external operating connections of the lamp.

In the drawings the lamp bracket 1 is shown as rigidly mounted on a portion of the chassis 2 of an automobile. A base 3 is rigidly secured to the bracket 1, and to 50 this is also rigidly secured a pedestal 4. The base 3 and pedestal 4 contain operating connections for causing both movements of the lamp, and the pedestal 4 also supports the lamp carrying cap or bracket 5.

55 Cap 5 comprises a generally disc form head portion 6, and a depending portion 7

having thereon a flange 8 which rotatably engages an annular extended portion 9 of the pedestal 4, and an inwardly disposed flange 11 for connection with a hollow 60 shaft or quill 12. Cap 5 and hollow shaft 12 are mutually secured in nonrotatable relation by means of bolts 13, passing through portion 7 of the cap and having thereon nuts 14 formed to bear against the inner surface 65 of shaft 12. Extended portion 9 of the pedestal 4 serves as a fixed seat for ball bearings 15, supported in a rotatable seat 16, for facilitating rotation of shaft 12 and cap 5 relatively to the pedestal. 70

The lamp proper (A) is supported by means of a limb 17, mounted on the curved outer surface of cap 5 and having a concave end portion 18 for the reception of the lamp.

The means for causing horizontal rotation 75 of hollow shaft 12, with consequent horizontal rotation of lamp supporting cap 5, comprise the following combination of elements.

Adjacent the lower extremity of hollow 80 shaft 12 a miter ring gear 19 is secured to the shaft by means of set screws 20 passing through a ring or hub 21 on the ring gear, the shank 22 of the gear, and the wall of shaft 12. Ball bearing 23, held in a rotatable seat 24 and in an annular fixed seat 25 in the pedestal 4, facilitates rotation of the gear and shaft relatively to the pedestal. 85

Meshing with miter ring gear 19 is a miter 90 gear 26 rotatable in a hub 27 in the base 3. A crank 28 fixedly secured to hub 27 serves to produce rotational movement of miter gear 26, and correspondingly of miter ring gear 19, hollow shaft 12, and lamp support 95 ing cap 5.

It is highly desirable, for reasons herein-after set forth, that the horizontal movement of the lamp be automatic and that it be produced directly by movement of the 100 steering mechanism of the vehicle. For this purpose the crank 28 is connected with the steering arm or lever 29 (Fig. 1 of the drawings).

These connections comprise a link 30 pivotally connecting crank 28 and operating sleeve 31, which is in turn connected with steering arm 29 by means of the links 32 and 33. Steering of the vehicle thus produces a horizontal rotation of the lamp (A). 110

It will be noted that the lamp supporting limb 17 is rotatable in a vertical plane on

the surface of the cap 5. Depending from limb 17 through a slot 34 in cap 5, is a crank 35, rotatable on a bolt 36 passing through the cap and having crank pin 37 joining it to connecting rod or link 38. Connecting rod 38 is joined at its lower extremity to clevis block 39, the base of which lies against the base of a second clevis block 40. A connecting rod or link 41 is joined by crank pin 42 to a crank 43, which is mounted on a squared shaft 44 in the base of the lamp. Clevis blocks 39 and 40 have thereon collars 45 and 46 respectively bearing against a sleeve 47 lying within and in engagement with the hollow shaft 12. The clevis blocks thus form a swivel so that horizontal rotation of the shaft 12 does not interfere with rotation of the lamp in a vertical direction.

20 Squared shaft 44 for transmitting motion to cause vertical rotation of the lamp lies within a centering bushing 48 disposed concentrically with the hub 27 of miter gear 26. This squared shaft has connected therewith at its outer extremity, a crank 49 for transmitting power for rotating the shaft and causing rotation of the lamp in a vertical direction. A rod 50 passing through operating sleeve 31 connects crank 49 with a second crank 51. Crank 51 is in turn connected with a third crank 52 by a short shaft 53 supported by bracket 54. Joined to crank 52 is an operating rod 55 extending along the steering column 56 and joining manually operable means thereon.

These means (shown in Figs. 1, 7, and 8 of the drawings) comprise a bracket 57, arranged to clamp upon steering column 56. Rotatably mounted on bracket 57 is a sleeve 58, which has arms 59 provided with eyes for the reception of operating rod 55, and arms 60. A handle or lever member 61 is mounted on a bolt 62 in the arms 60 so that it may be rotated in a direction normal to the direction of rotation of sleeve 58. Bracket 57 also carries a stationary ratchet segment 63 with which engages a pawl or tooth 64 on handle 61. A flat spring 65 serves to normally maintain pawl or tooth 64 in engagement with ratchet 63.

With this structure handle 61 may be rotated in one direction to lift pawl 64 out of engagement with ratchet 63, and then caused to rotate sleeve 58 for producing movement 55 of operating rod 55.

As it is usual to mount two lamps upon a vehicle, the mechanism is so arranged that both movements of one of the lamps may be produced by similar movements of the other thereof. This arrangement is shown in Fig. 2 of the drawings. As shown, both of the lamps are fastened to a cross bar 66, which has thereon anchor plates 67 to be secured to the mud-guards of a vehicle. This 65 steady bar 66 is bolted to screw threaded

bosses 66^a on the pedestals 4, as shown in Figs. 3 and 4 of the drawings.

It is to be understood that all the operating mechanism of one lamp assembly is duplicated in the other thereof, with the exception of the cranks 28 and 49 and the operating connections therefor.

Power for causing rotational movement in a horizontal plane is transmitted from the directly operated lamp assembly to the other member of the pair by means of a hollow shaft 69 carried on a flanged hub 70. A bushing 71 is secured to the hub 70 by means of set screws 72 passing through a flange 73 on the bushing. Passing longitudinally 75 through bushing 71 are a plurality of bolts 74 which secure the bushing to one of the side disks 75 of a double crank 76, the other disk 77 of which is secured by means of similar bolts 78 to a bushing 79 through 80 holes in hub 27 of miter gear 26; rigidly 85 uniting gear 26, hub 27, and crankarm 77; and also uniting crank 28 to hub 27.

The double crank structure is illustrated in Figs. 9, 10, and 11 of the drawings. As shown, the side disks 75 and 77 are provided with bolt holes 90 for the passage of the bolts 74 and 78, while the crank arm or crank proper 76 is eccentrically mounted between the disks. By means of this arrangement, the crank for transmitting movement for horizontal rotation does not interfere with movement of squared shaft 44 and crank 43 thereon.

In order to transmit motion for causing 100 vertical rotation of the lamp carrying limb of the lamp assembly which is not directly actuated, squared shaft 44 is continued through hollow shaft 69 and engages in the centering bushing 48 of the idling assembly. 105

The mechanism described above is such that the driving lamps of a vehicle are automatically turned with steering of the vehicle to illuminate the roadway which the vehicle is about to traverse. The inside ditch on 110 curves is thus illuminated; and the light is cast into ravines or cuts which the vehicle is approaching, or is cast around built-up corners of city streets. Other drivers are thus warned of the approach of a vehicle. 115

It will be understood that with the lamps described a vehicle runs into its own light while rounding curves, and that the illumination is not cast uselessly ahead or along a roadway which the driver of the vehicle 120 does not intend to follow. The lever ratios may also be varied so that the angular swing of the lamps in a horizontal direction is greater than, less than, or equal to the angular swing of the front wheels of the 125 vehicle. Preferably the swing of the lamps is equal to or greater than that of the front wheels in order to secure the full advantage of the special lamps in rounding curves and the like.

It is desirable to take the power for swinging the lamps horizontally at a point as close as possible to the steering column in order that play or lost motion in the operating connections may not diminish the steadiness of the lamps. The steering arm or lever thus provides a convenient point for the attachment of these connections.

The rotation of the lamps in a vertical direction is also of great advantage in securing the desired full illumination of the roadway, together with the ability to so depress the lights that a blinding glare will not be cast into the eyes of the driver of an approaching vehicle or upon the wind shield of a vehicle ahead. The mounting and actuating means for rotation in a vertical direction thus avoid any practical necessity for the use of special lenses or other means attached directly to the lamps themselves.

It is to be noted that this manually produced vertical rotation of the lamps may be simultaneous with the automatic horizontal rotation thereof, so that the lamps may be conveniently depressed while the vehicle is on a curve. The two movements are also entirely independent of each other.

As it is possible to make a number of modifications in the form and arrangement of the parts without departing from the spirit of the present invention, no limitations are to be imposed upon the scope of the invention other than those contained in the claims appended hereto.

What we claim is:

1. In a lamp assembly for vehicles the combination of a lamp column, a member rotatable about a vertical axis within said column, a slotted cap mounted on said member to rotate therewith, a lamp supporting member rotatable on said cap about a horizontal axis and having a limb extending through the slot in the cap into the interior of the lamp column, connections for transmitting movement of rotation to said cap, and independently operable means connected with said limb for transmitting movement of rotation to said lamp supporting member.

2. In a lamp assembly for vehicles the combination of a lamp pedestal comprising a base, a column, and a cap mounted on said column for rotation about a vertical axis; said base, column, and cap forming a continuous housing; a lamp supporting member mounted on said cap for rotation about a horizontal axis, and means lying wholly within the housing formed by said base, column, and cap for independently imparting movement of rotation to said cap and to said lamp supporting member.

3. Driving lights for vehicles comprising a pair of horizontally aligned lamp assemblies each having lamps mounted for both horizontal and vertical rotation, a positively actuated crank shaft in one assembly for

actuating the mechanism causing horizontal rotation of the lamp thereof, a hollow shaft for transmitting such motion to the other assembly, a shaft lying within the crank shaft and transmitting shaft arranged to 70 actuate the mechanism for causing vertical rotation of the lamps of both assemblies, and double cranks in said crank shaft and hollow shaft for permitting operation thereof without interference with the operation of the 75 other of said shafts.

4. In a lamp assembly for vehicles the combination of a base, a lamp column, a sleeve within said column and rotatable about a vertical axis, a slotted cap rigidly 80 mounted on said sleeve to rotate therewith, a lamp supporting member rotatably mounted on said cap and having a limb extending through the slot therein, two positively actuated shafts disposed horizontally 85 in said base, connection between one of said shafts and said sleeve for producing rotation of the sleeve and cap about a vertical axis, and connection between the other of said shafts and the lamp supporting member for 90 producing rotation of the latter about a horizontal axis; said connections lying wholly within the housing formed by said base, column, and cap.

5. In a lamp assembly for vehicles the combination of a base, a lamp column, a sleeve within said column and rotatable about a vertical axis, a slotted cap rigidly mounted on said sleeve to rotate therewith, a lamp supporting member rotatably mounted on 100 said cap and having a limb extending through the slot therein, two positively actuated shafts disposed horizontally in said base, connection between one of said shafts and said sleeve for producing rotation of the 105 sleeve and cap about a vertical axis, and a swivelled rod connecting the limb of the lamp supporting member to the other of said shafts for producing rotation of the lamp supporting member about a horizontal axis independently of movement of the sleeve and cap; said connections lying wholly within the housing formed by said base, column, and cap.

6. In a lamp assembly the combination of a rotatable sleeve, a lamp carried by said sleeve 115 and rotatable in a direction normal to the direction of rotation of the sleeve, a horizontal shaft, an intermediately swivelled rod connected with said shaft and with said lamp for rotating said lamp in a direction normal to the direction of rotation of said sleeve, a shaft and connections for rotating said sleeve, and a double throw crank on said shaft for permitting independent actuation 120 of the connections for producing vertical 125 rotation of the lamp.

7. In a lamp assembly for vehicles the combination of a base, a vertical pedestal on said base, a horizontally rotatable sleeve in said pedestal, a ring gear on said sleeve, 130

a lamp mounted on said sleeve and vertically rotatable thereon, concentric shafts in said base, a gear on one of said shafts meshing with said ring gear for producing horizontal rotation of said sleeve, and operating means connected with the other of said shafts and extending through said ring gear for producing vertical rotation of said lamp.

8. In a lamp assembly for vehicles the combination of a base, a vertical pedestal on said base, a horizontally rotatable sleeve in said pedestal, a ring gear on said sleeve, a lamp mounted on said sleeve and vertically rotatable thereon, concentric shafts in said base, a gear on one of said shafts meshing

with said ring gear for producing horizontal rotation of said sleeve, and operating means comprising an intermediately swivelled connecting rod connected with the other of said shafts and extending through said ring gear for producing vertical rotation of said lamp. 20

In testimony whereof, we hereunto set our hands.

DAVID CHALMER SHARP.
WALTER R. DIEHL.
